UNITED STATES PATENT OFFICE.

ROY C. NEVIN, OF OAKLAND, CALIFORNIA.

TELEPHONE CALLING DEVICE.

1,038,419.

Specification of Letters Patent. Patented Sept. 10, 1912.

Application filed August 10, 1911. Serial No. 883,884.

To all whom it may concern:

Be it known that I, Roy C. Nevin, citizen of the United States, residing at Oakland, in the county of Alameda and State of California, have invented a new and useful Telephone Calling Device, of which the following is a specification in such full and clear terms as will enable those skilled in the art to construct and use the same.

This invention relates to a make and break apparatus for electrical circuits, and its object is to produce an apparatus which will permit the user to ring any one of a given series of numbers, while preventing him from interfering with the timing of the circuit breaking apparatus.

Another object of the invention is to provide a circuit breaking apparatus which will be as simple as possible, and which will prevent the circuit from being broken while the circuit breaking apparatus is moving from the position of rest to the desired number.

In the drawings in which the same numeral of reference is applied to the same portion throughout the several views, Fig. 1 is a front elevation of a telephone standard having a circuit breaker therein, Fig. 2 is a vertical longitudinal sectional of a portion of the telephone standard, showing the interior thereof, Fig. 3 is a plan view of the telephone standard in horizontal section, Fig. 4 is a vertical sectional view of the telephone standard at right angles to Fig. 2, Fig. 5 is a view looking at the side of the spring contact makers and the block to which they are connected, Fig. 6 is a view of one of the contact making springs, Fig. 7 is a side view of the spring shown in Fig. 6, Fig. 8 is a plan view of the middle spring, Fig. 9 is a side elevation of the middle spring, Fig. 10 is a plan view of one of the outside springs, Fig. 11 is a side elevation of the spring shown in Fig. 10, and Fig. 12 is a vertical sectional view of the piston, showing the contact making and breaking rack.

In Fig. 1 there is shown a front elevation of a telephone standard 1 having a base 2, receiver 3, transmitting device 4, and receiver hook 5, all of which is well-known in the art.

Secured on the front of the telephone standard is a semi-circular tube 6, having a long slot 7 at one side thereof and a series of short slots 8, adjacent each of the latter of

which are a series of numbers, as A¹, B², C³, etc. The tube 6 is suitably secured to the telephone standard 1 by means of screws, and it covers a wide slot in said standard.

Secured within the standard is a cylinder 9, said cylinder having a screw 10 which is passed therethrough to regulate the size of an air escap. opening 11 and a small spring-pressed valve 12 in the bottom thereof to permit the free upward movement of the piston 13. The piston 13 is provided with a rack 14 having the desired number of projections thereon to produce the necessary breaks of the circuit, and it has a finger catch 15 projecting therefrom, which finger catch extends far enough out from the standard to be easily picked up when necessary.

Secured near the top of the standard 1 is a block 16, screws 17 in slots thereof permitting the adjustment of said block to adjust the position of the three contact-making members 18, 19 and 20, to each of which the wires 21, 22 and 23 are connected.

The object of the spring member 18, which has a small roller 25 thereon at the lower end, is to short circuit out the wires leading to the transmitter and receiver of the telephone, when it is desired to call up any number. This occurs because the curved guard wire 26 on the inside of the piston 13 moves away from the roller 25, thus permitting the contact point 26' to touch the spring 20, breaking the contact of the latter with the screw 27. The bottom of the spring 19 carries a block of hard material as 27', which is intended to be struck by the points of the rack 14.

It will be noted that the guard wire 26 (see Fig. 3) is so curved as to always hold the contact plate 13 away from contact with the plate 20 when the piston is down, whether turned to the position shown in Fig. 1 or in any of the other possible positions to which the piston may be moved, the ends of said wire being secured to the piston 13. It will be understood by those skilled in the art that the wires 21, 22 and 23 will be passed down the inside of the standard as may be desired.

In operation, the user lifts the finger hold 16 as high as the desired number, say C³, whereupon he passes it through the slot opposite C³ and permits it to fall down to its initial position. Inasmuch as the finger hold is back of the tube 6, at that time, it is impossible for the user to accelerate the

fall of the piston, and thus confuse the operation of the apparatus at the central station.

Another advantage that is gained by this apparatus lies in the fact that as soon as the finger hold 15 has been rotated to the left, Fig. 1, so that it can be raised, its rack 14 will entirely miss the point 27, thus making it possible to lift the rack without 10 making and breaking a circuit and without the use of a pivoted pawl on the spring 19.

Having thus described my invention what I claim as new and desire to secure by letters patent of the United States, modifications within the scope of the claims being expressly reserved, is as follows:—

1. In a circuit breaking device, electrical circuits, a spring connected therewith, said spring having a contact point, a cylinder, 20 a piston in said cylinder having a rack with projections thereon, a finger catch connected with said piston, a slot in the standard through which said finger catch passes, and a slotted guard for said finger catch through 25 any one of which slots said finger catch may be passed to break the circuits a given number of times, substantially as described.

2. In a circuit breaking device, electrical circuits, a spring connected therewith, said 30 spring having a contact point, a cylinder, a piston in said cylinder having a rack with projections therein, a finger catch connected with said piston, a slot in the standard

through which said finger catch passes, and a slotted curved guard secured to the standard, substantially as described.

3. In a circuit breaking apparatus, a telephone standard having electrical circuit wires, a cylinder, a piston in said cylinder and having a rack within the piston, a finger catch connected with said piston and projecting outwardly through a slot in the standard, an outwardly curved guard having a plurality of slots therein and through any one of which the finger catch may be 45 passed to break the circuit a number of times, substantially as described.

4. In a circuit breaking apparatus, a telephone standard, electrical circuits therein, a spring to which one of said circuits is 50 connected, a cylinder within the standard, a piston within the cylinder to regulate the timing of the circuit breaking apparatus and a guard wire concentric with the piston to break one of the electrical circuits when 55 the piston is down, substantially as described.

In testimony whereof I have hereunto set my hand this 2d day of August A. D. 1911, in the presence of the two subscribed 60 witnesses.

ROY C. NEVIN.
